UNITED STATES PATENT OFFICE.

EDWIN BENJAMIN, OF SOUTH EVANSTON, ILLINOIS.

PLANER-KNIFE.

SPECIFICATION forming part of Letters Patent No. 293,135, dated February 5, 1884.

Application filed April 16, 1883. (No model.)

To all whom it may concern:

Be it known that I, EDWIN BENJAMIN, a citizen of the United States, residing at South Evanston, in the county of Cook and State of Illinois, have invented a certain new and useful Improvement in Planer-Knives, of which the following is a full, clear, concise, and exact description, reference being had to the accompanying drawings, forming a part of this specification.

My invention consists in a planer-knife in which that portion of the knife which is next to the cutting-edge is lightened by reducing the quantity of metal therein, whereby the centrifugal force is more evenly distributed over the different portions of the knife when it is being revolved by the cylinder to which it is attached.

Planer-knives, when revolved on a cylinder in the usual manner, necessarily travel faster at the cutting-edge than at the heel or at any other part of the knife, because the cutting-edge must project beyond the other portions of the knife or cylinder, in order to do the cutting, and therefore travels in a greater circle. This difference in velocity between the front and rear portions of the knife on high-speed cylinders amounts in some cases to over a thousand feet per minute. The knives are usually bolted to the cylinder near their centers, so that the weight of each knife is distributed on each side of its fastening-bolts, with usually a preponderance of weight on the side next to the cutting-edge. The front portion of the knife traveling at the greater velocity, its momentum will be much greater than that of the rear portion. The centrifugal force, acting on the front or cutting portion, is therefore much greater than that acting upon the heel of the knife. The consequence is a tendency of the front portion of the knife to throw away from the cylinder. In my improved knife I have sought to overcome this difficulty by decreasing the weight of the front portion of the knife, and thereby decreasing the centrifugal force acting thereupon, thus more evenly distributing the effect of the centrifugal force over the different portions of the knife.

In the accompanying drawings, Figure 1 is a view of a knife embodying my invention, shown attached to a cylinder in the ordinary manner, the different paths in which the front and rear portions of the knife travel being indicated by dotted lines. Fig. 2 is a plan view of the knife detached. Fig. 3 is a transverse sectional view of the same, taken on line *x x*; and Fig. 4 is a partial longitudinal sectional view on line *y y*.

In the said drawings, *A* represents the knife; *B*, the cylinder, to which it is secured in the ordinary manner by a bolt, *C*. *a a* represent the path of the cutting-edge, and *b b* that of the heel of the knife.

The manner in which I have shown my invention carried out is by constructing the knife with a series of transverse flutes, *s*, which extend from near the center of the knife to the cutting-edge. By this construction I am enabled to considerably lighten this portion of the knife and at the same time retain the requisite amount of strength and stiffness. The flutes may be of any desired shape or size to attain the desired result. I do not, therefore, limit myself to any particular shape or number.

The knife may be provided with the ordinary slots, *t*, through which the bolts pass in securing it to the cylinder; or it may be secured in any other suitable manner.

A knife constructed with the flutes as above set forth is much easier ground than a plain knife of the ordinary type, there being less stock to grind away.

Having thus described my invention, I claim—

1. A planer-knife adapted to be secured by fastening-bolts at or near its center to a revolving cylinder, said knife having that portion which extends forward from the fastening-bolts to the cutting-edge lightened, substantially as described, whereby the momentum of the forward portion of the knife is reduced.

2. A planer-knife adapted to be secured at or near its center to a revolving cylinder, said knife being provided with a series of transverse flutes extending from near the cen-

ter of the knife toward the cutting-edge, whereby said knife is lightened, substantially as and for the purpose specified.

3. The combination, in a planer-knife adapted to be bolted to a revolving cylinder, of the slots *t*, through which the fastening-bolts pass, and the transverse flutes extending from near the center of the knife toward the cutting-edge, substantially as described.

In witness whereof I hereunto subscribe my name this 9th day of April, A. D. 1883.

EDWIN BENJAMIN.

Witnesses:

DANL. H. PATRICK,
PAUL A. STALEY.
